RAZOR BLADE SHARPENER

Joseph A. Doll, Mineola, N. Y.

Application May 27, 1942, Serial No. 444,614

4 Claims. (Cl. 51—59)

This invention relates to a razor blade sharpener that is particularly suitable for sharpening a double edged safety razor blade.

It is well known that the cutting edges of razor blades are not perfectly smooth but that under a microscope the edges are seen to be made up of small teeth which are in alignment when the blade is sharp but become bent or out of alignment when the razor is used, thus causing the blade to become what is commonly referred to as dull.

By the present invention razor blades are easily and quickly sharpened, or put into condition for use, without requiring any honing or wearing away of the blade by removal of metal by abrasion. The edges of the blades are smoothed and thus "sharpened" by rubbing contact with glass or other non-abrasive material, although abrasive can be used or abrasive paste can be applied to the blade engaging surfaces of the sharpening elements to hone the edges whenever needed.

In carrying out this invention the razor sharpening elements are installed in a holder or container that can be manipulated with one hand and both edges of the blade sharpened without removing the blade from the sharpener.

The invention will be understood from the description in connection with the accompanying drawing, in which:

Fig. 1 is a perspective view of the device;

Fig. 2 is a section along the line 2—2 of Fig. 1;

Fig. 3 is a section on an enlarged scale along the line 3—3 of Fig. 2;

Fig. 4 is a plan view of one half of the device;

Fig. 5 is a plan view of the other half of the device;

Fig. 6 is a plan view of one of the sharpening elements;

Fig. 7 is an edge view of the same;

Fig. 8 is a plan view of a modification; and

Fig. 9 is a section along the line 9—9 of Fig. 8.

In the drawing, reference character 1 indicates one half or portion of a box, or container, for holding a razor blade in position to be sharpened and for applying the sharpening elements to the blade for sharpening it. Reference character 2 indicates the other portion of the box. This box may be made of wood or any other suitable material that is rigid and will retain its shape.

A strip 3 rectangular in cross section is fitted in notches 4 in the middle of the upper edges of the end walls of the section 1 of the box, and may be fastened in place by small nails 5 or

by glue or by means of a tight fit. A rib or projection 6 of a size to fit the longitudinal opening in a safety razor blade is provided along the middle of the strip 3.

5 A corresponding strip 3' is fitted in notches 4' in the middle of the edges of the end walls of the section 2 of the box and is held in place in a similar manner to that of strip 3. A slot 7 is provided in the strip 3' to receive the rib 6.

10 A pair of duplicate blocks 10, which are preferably, though not necessarily, made of glass, are located in the sections 1 and 2 inside the strips 3 and 3'. They are so shaped and located that they serve as sharpening members or devices for razor blades as will be described below.

Each block 10 is almost as long as the inside of the box that is made up of the sections 1 and 2, and is sufficiently narrower than the inside of this box to allow appreciable lateral movement in the box when the box is shaken laterally.

15 A longitudinally extending centrally located cutout portion 12 is provided in the face of each block 10. These cut-out portions are wide enough and deep enough to prevent the blocks from striking the strips 3 or 3' when the blocks are moved laterally in the box.

The portions of the blocks 10 on opposite sides of the cut-out portions 12 are made sloping from 20 the edges of the blocks (Fig. 3) to the cut-out portions 12. These sloping portions 13 are formed with rounded parallel ribs 14 extending at an oblique angle to the side edges of the blocks and, therefore, to the edges of a blade positioned in the box. An angle of about 35° has been found to work well, although this is not critical.

25 Since the ribs 14 all slant in the same direction when the blocks face in the same direction, as in Figs. 4 and 5, when the two sections of the box are placed together with the blocks facing each other the ribs of the two blocks will then slant in opposite directions and the edges of a blade in the closed box after being rubbed on one side by ribs slanting in one direction will when 30 the box is turned over be rubbed on the other side by ribs slanting in the other direction. This results in a more effective smoothing of the blade edges.

The operation is as follows:

35 With the box open a razor blade 15 is placed upon the cross piece 3 of the section 1 of the box to cause the rib 6 to extend through the slot 16 in the blade. The section 2 of the box is then put on so that the slot 7 in its cross piece 55 3' receives the rib 6, thus keeping the two sec-

tions of the box aligned and causing the sloping ribs 14 on the upper block 10 to rest upon the edges of the blade 15. The box is then shaken to and fro laterally a few times, that is, in a direction transverse of the edges of the blade 15, whereupon the ribs smooth or straighten out the bent or jagged teeth on both edges on that side of the blade. The wrist of the user is then turned, or the box is turned over in any other way, and the shaking operation is repeated to straighten out the teeth on the other side of the blade by means of the other block 10 as the ribs 14 thereof then contact with the blade, thus finishing the sharpening of both edges of the blade.

The inward slope of the edges of the ribs 14 is preferably made to correspond to but slightly greater than the bevel at the edges of the razor blade, as indicated in Fig. 3, since the blades are flexible and are slightly bent by the weight of the block 10 that is at the moment in use.

When it is desired to hone the blade, a honing paste is applied to the ribs 14 and the same operation is performed as that described above for sharpening the blade, whereupon honing takes place, the edges of the blade being abraded. The paste can then be removed from the ribs 14 and the usual razor blade sharpening can be effected.

In the modification shown in Figs. 8 and 9 reference character 20 indicates a box with its end walls cut out as shown at 21. It is provided at the bottom thereof with a support 22 for a razor blade 24. This support has pins or projections 23 to extend through corresponding holes in the razor blade, although a strip may be used to fit the razor blade slot as described above.

In operating the device as shown in Figs. 8 and 9, a blade is placed upon the support 22 in the box, the sharpening block 10 is placed on the blade and the box is shaken sidewise a few times. The block is then removed, and the blade is turned over, and the block put on again. The box is then shaken a few more times, whereupon the razor blade is ready to be used.

The material that has thus far been found to be most suitable for making the blocks 10 is opal glass. This particular glass follows the mold accurately without bubbles forming and thus providing the desired smooth and hard surface. However, other glass having such properties or any material that is very dense and hard and can have an accurate smooth surface imparted to it may be used.

What is claimed is:

1. A safety razor blade sharpener, comprising a

container having means to position and support a double edge razor blade in fixed position therein with its edge portions free, and two laterally reciprocable blade sharpening blocks in said container on opposite sides of the supported blade one free to rest on one side of the blade when the container is in one position and the other free to rest on the other side of the blade when the container is in a reversed position, each of said blocks having sloping and diagonally ribbed blade-engaging surfaces.

2. A safety razor blade sharpener, comprising a container having means to position and support a double edge razor blade in fixed position therein with its edge portions free, and two laterally reciprocable blade sharpening blocks in said container on opposite sides of the supported blade one free to rest on one side of the blade when the container is in one position and the other free to rest on the other side of the blade when the container is in a reversed position, each of said blocks having sloping and diagonally ribbed blade-engaging surfaces of smooth hard material.

3. A safety razor blade sharpener, comprising a container having means to position and support a double edge razor blade in fixed position therein with its edge portions free, and two laterally reciprocable blade sharpening blocks in said container on opposite sides of the supported blade one free to rest on one side of the blade when the container is in one position and the other free to rest on the other side of the blade when the container is in a reversed position, each of said blocks having sloping and diagonally ribbed blade-engaging surfaces of smooth hard material, the ribs of the two blocks sloping in opposite directions when the blocks are in the container and the container is closed.

4. A safety razor blade sharpener, comprising a container consisting of two open box parts adapted to be placed together to form a closed container, each of said box parts having a blade-holding strip extending across its open side one of which strips has blade-positioning means projecting therefrom, and a laterally reciprocable blade sharpening block in each of said box parts, one of said blocks being free to rest on one side of a blade positioned in the closed container when the container is in one position and the other being free to rest on the other side of the blade when the container is in a reversed position, each of said blocks having sloping and diagonally ribbed blade-engaging surfaces of smooth hard material.
